UNITED STATES PATENT OFFICE.

EDWARD THOMAS, OF NEW YORK, N. Y., ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,287,517.

Specification of Letters Patent. Patented Dec. 10, 1918.

Application filed December 13, 1912. Serial No. 736,452.

To all whom it may concern:

Be it known that I, EDWARD THOMAS, a citizen of the United States, residing in New York, in the county of New York and 5 State of New York, have invented certain new and useful Improvements in Combined Type-Writing and Computing Machines, of which the following is a specification.

This invention relates to computing machines in which numeral keys are operated to set certain computation pins, the latter being subsequently employed to determine the extent of movement of the dial wheels or devices. 10 The improvement is especially adapted to combined typewriting and computing machines, and it is illustrated in connection with the Underwood-Hanson machine of this type. 15 In said machine each dial wheel is provided with a rack bar whereby it is operated; and upon each rack bar are nine pins. The keys are connected to devices for setting any of the nine pins on any of the rack bars. 20 As illustrated in patent to Hanson No. 905,421, dated December 1, 1908, the pins have been mechanically held down whenever depressed by the keys. In another form of 25 said invention, means are provided so that when any pin on a given rack bar is depressed, said pin will automatically release any previously depressed pin on said bar, thus making it unnecessary to have a special error key for making a correction. In carrying out this feature of said form, each 30 computation pin, when depressed, is latched down by means of a universal latch, namely, a latch which is universal to all the pins of one bar. The construction is such that the depression of any pin first releases said 35 latch, and hence releases any previously set pin, while at the conclusion of the depression of the pin, the latch snaps into position to lock the depressed pin down. 40 Each of the pins in said form of the invention is spring-pressed, normally tending to return to ineffective position, so that the release of the latch restores every pin to ineffective position. In said form of the invention, the rack bars are operated, as is 45 usual, by a general operator, after the numeral keys have been depressed for writing and setting up any given number; and at the conclusion of the movement of said gen-

eral operator, means are provided for operating the latches of all the bars, so as to release all the pins, and the springs return all the depressed pins back to their ineffective positions. 55

In said Underwood-Hanson machine there 60 is one rack bar for each denomination, and according to the present invention the universal latch on each rack bar is provided with means for connecting it to the zero numeral key, so that the depression of said zero 65 key will release all the pins set on any given rack bar at any one time. Said connection may be in the form of an idle pin on the rack bar comprising a cam, which, like the cams on the other pins, moves its universal 70 latch to ineffective position. Said zero pin, however, is preferably not provided with any catch by which it may be held by said latch. Thus the mere depression of the zero 75 key, when any rack bar is in effective position, will release any set pins on said rack bar and thus provides that the operation of any numeral key, even though it be the zero key, will correct any previously made error in any denomination. 80

Other features and advantages will hereinafter appear. 85

In the accompanying drawings,

Figure 1 is a sectional side elevation from front to rear of an Underwood-Hanson combined typewriting and computing machine. 85

Fig. 2 is a plan of certain jacks for determining the order of operation of the computation-pin bars.

Fig. 3 is a part sectional side elevation of a computation pin bar, showing one of the pins as latched down and the others in normal positions. 90

Fig. 4 is a part sectional perspective view of a portion of the pin bar, showing the first 95 pin thereon as latched down and about to be released by the zero pin.

Fig. 5 is a perspective view to illustrate the devices connected to the general operator for automatically releasing the depressed 100 pins at the conclusion of the cycle of movements of the general operator.

Fig. 6 illustrates the preferred form of a computation pin.

Fig. 7 is a sectional side elevation illustrating the pin-releasing movement of the 105 general operator.

Alphabet keys 1 and numeral keys 2, pro-

vided upon the forward ends of levers 3, are operated to rock bell cranks 4 to swing type bars 5 up against a platen 6. The platen is mounted upon a carriage 7, which is propelled by a spring barrel 8 and controlled in the usual manner by an escapement wheel 9 and dogs 10, the latter operated by a universal bar 11, which is driven by wheels 12 on the type bars. Dial wheels 13 are operated by pinions 14, which mesh with racks 15 formed upon bars 16, one bar for each dial wheel, each bar carrying a set of computation pins 17, which are depressible by linkages 18, the latter including rock shafts 19 which have the usual arms 20 engageable by stems 21 pendent from the numeral keys 2. Depression of any numeral key 2, except the zero key, to operate its type bar causes the depression of the corresponding linkage 18, whereby one of the pins 17 is depressed in the path of a bar 22 on a general operator 23, which may be operated by a crank 24 after all of the desired pins 17 have been set. The crank is fixed upon a rock shaft 25; and the shaft carries a segmental gear 26, which meshes with an idle pinion 27, the latter meshing with the rack 23 and forming part of the general operator for turning the computing wheels. In order to be able to depress or set one of the pins 17, however, its bar 16 must be lifted above the other bars; and this is done by a denomination-selecting mechanism, which is controlled by the typewriter carriage 7, in conjunction with the numeral keys 2.

Upon the carriage is a dog 28, which, during the letter-feeding movements of the carriage, raises denomination-selecting jacks 29 one after another, and these jacks depress links 30 whose lower ends are pivoted to levers 31 which operate linkages 32 to elevate the pin-carrying bars 16; the linkages 32 forming a transposition device whereby the order of operation of the bars 16 is reversed, the extreme right hand jack 29, which is the first to be operated, causing the lifting of the extreme left hand pin bar 16, as usual.

Each of the bars 16 is provided with a series of vertical perforations 33 to form bearings for the body portions 34 of the computation pins 17; and said perforations 33 may be of square form as illustrated, although the invention is not limited to such form.

The pins are held up in normal positions by compression springs 35 which bear up under heads 36 secured upon the tops of the pins and are engageable by the linkages 18. At their lower ends the springs 35 bear upon a plate 37 which is supported upon the bar in raised position, being fixed to lugs or elevations 38, 39, 40 formed or provided on the pin bar 16. The upward or return move-

ment of each pin is limited by a shoulder 41 formed thereon.

Whenever any computation pin 17 is depressed, its shoulder 41 catches under a latch 42, so that the pin is held down. This latch 70 42 is adapted to latch down any of the pins, and hence is in the nature of a universal latch. It may be formed of a strip of a sheet metal mounted to slide endwise along the bar 16 and having a series of perforations 43, one for each of the computation pins 17. A draw spring 44 is connected at one end to the universal latch and at the other end to the part 40 of the bar 16, and tends constantly to move said latch to pin-locking position. The septums 45 between the perforations 43 are the members which lock the pins down; and they are preferably beveled as at 46, and each shoulder 41 has a beveled under side, as at 47, so as to cam the 85 universal latch forwardly during the depression of any pin. At the completion of the down stroke of the pin, the universal latch 42 snaps rearwardly and catches over the shoulder 41, as seen at Figs. 3 and 4. 90 The computation pin is thereby held down until it can be engaged by the cross bar 22 of the general operator, when it serves as a lug whereby said cross bar advances said bar 16 and rotates the dial wheel 13. 95

The perforations 43 in the universal latch 42 are elongated to permit the necessary shifting of the latch. The latter may be confined at one end in a slot 48 in the lug 38, and at the other end may work in a 100 bearing 49 in the bottom of lug 39; or the latter may be secured to the bar 16 by means of a pin 50, passing through a slot 51 in the end of said latch bar or member 42. If an error has been made, the operator need not 105 press the error key, but may, after resetting the typewriter carriage, immediately strike the right numeral key; and the depression thereof will force down another one of the pins 17, and the cam 47 on the latter will 110 force forwardly the latch bar 42, causing the latter to release the previously depressed pin, so that the latter is automatically returned to normal position by its spring 35; and the spring 44 will snap the latch 42 under the newly depressed pin, locking the same down in working position. If resetting the typewriter carriage back does not elevate the proper rack bar 16, the operative may set the carriage back several spaces and 115 then use the space key usually found in type-writing machines to bring the carriage to elevate the correct bar. The pins are shown as fitting loosely in the bearings 33 in the bar, but it will be understood that the fit 120 will be close enough to insure proper operation of the parts. Each pin may, if desired, be formed with a slight projection 52, Fig. 6; to give the latch 42 a little additional release motion, to insure that the previously 125 130

depressed pin shall be released; the edge of the pin sloping both upwardly and downwardly from the top of the projection 52 to form cams for this purpose.

5 Upon the completion of the return stroke of the general operator 23, a cam 53 thereon engages a wrist 54 provided on an arm 55 and lifts said arm together with a plate or bar 56 which is carried partly by said arm 10 and partly by a companion arm 57, Fig. 5; said arms fixed upon a rock shaft 58 suitably mounted in the framework. The bar 56 is elevated to the Fig. 7 position during the conclusion of the return stroke of the general 15 operator 23, and lifts up all of the set of pins 59 provided one upon each of the bars 16 in front of the computation pins 17. Each of these pins 59 has a cam portion 60 which passes up through a perforation 61 in 20 the associated universal latch bar 42, and said cam portion 60 engages the forward edge of the slot 61 and forces the latch 42 forwardly to a position to release any pin that it may be latching down; whereby it is 25 insured that all the pins shall be in normal positions at the conclusion of the return stroke of the general operator. During the final portion of said return stroke, the wrist 54 runs off from the cam 53, and the releasing 30 bar 56 drops, and individual springs 62 return the released pins 59 to normal positions. During the next forward stroke of the general operator 23, the cam 53 rotates about its pivot 64 without lifting the releasing 35 bar 56; and a spring 65 then returns cam 53 to normal position.

In addition to the computation pins 17, each rack bar also comprises a zero computation pin 66 which is operated like the other 40 keys from a linkage 18, said linkage being operated by a pendent 21 depending from the zero numeral printing key. When said pin 66 is depressed, a cam face 67 thereon moves the latch 42, as do the cam faces of the 45 pins 17, so that depression of said pin 66 will release any pin 17 previously set in said bar. Said pin 66 above its cam surface 67 has a flat surface 68 parallel to its length, which flat surface holds said latch 42 in the ineffective 50 position of the latch. Said flat surface 68 is advantageously of such length that the pin 66 cannot be depressed far enough to be caught by the latch 42. From this it results that the depression of the pin 66 by the zero 55 key will permit any previously set pin of a given rack bar to be reset by its spring, while on the return stroke of said zero numeral key, the spring 35, encircling the zero pin 66, will return said zero pin to its normal 60 ineffective position thus leaving no pin set on the rack bar.

In order to accommodate the flat surface 68, the plate 37 in which the upper ends of pins 17 and 66 are guided, may be slightly 65 offset, as seen in Figs. 3 and 4: and the head

69 of the pin 66 may be thinned as best seen in Fig. 3, so as to allow room for the free compression of the spring 35 around the pin 66.

Variations may be resorted to within the 70 scope of the invention, and portions of the improvements may be used without others.

Having thus described my invention, I claim:

1. In a combined typewriting and computing machine, the combination with numeral wheels, nine numeral printing keys and a zero printing key, of a letter-feeding carriage under the control of all of said keys, a set of denominational rows of indexing devices settable by said nine numeral keys, means controlled by said carriage for determining in which denominational row an indexing device shall be set by any of said numeral keys, means to enable the set indexing devices to determine the extent of rotation of the wheels, means operated by the depression of any of said numeral keys to print, to set its own indexing device and restore any previously set indexing device, and means operable by the depression of said zero key to print, to restore any previously set indexing device in any denominational row selected by said carriage.

2. In a combined typewriting and computing machine, the combination with numeral wheels, nine numeral printing keys and a zero printing key, of a letter-feeding carriage under the control of all of said keys, a set of denominational rows of indexing 95 devices settable by said nine numeral keys, means controlled by said carriage for determining in which denominational row an indexing device shall be set by any of said numeral keys, means to enable the set indexing 100 devices to determine the extent of rotation of the wheels, means operated by the depression of any of said numeral keys to print, to set its own indexing device and restore any previously set indexing device, and 105 means operable by the depression of said zero key to print, to restore any previously set indexing device in any denominational row selected by said carriage.

3. In a combined typewriting and computing machine, the combination with numeral wheels, nine numeral printing keys and a zero printing key, of a letter-feeding carriage under the control of all of said keys, a set of denominational rows of indexing 115 devices settable by said nine numeral keys, means controlled by said carriage for determining in which denominational row an indexing device shall be set by any of said numeral keys, means to enable the set indexing 120 devices to determine the extent of rotation of the wheels, means operated by the depression of any of said numeral keys to print, to set its own indexing device and restore any previously set indexing device, and 125 means under the joint control of said carriage and said zero key when operated to print to restore any previously set indexing device in any denomination.

zero device for each denominational row of indexing devices, and a universal bar operated by the zero key when operated to print and acting on all the zero devices to restore any previously set indexing device in any denominational row selected by said carriage.

4. In a combined typewriting and computing machine, the combination with numeral 10 wheels, nine numeral printing keys and a zero printing key, of a letter-feeding carriage under the control of all of said keys, a set of denominational rows of indexing devices settable by said nine numeral keys, 15 means controlled by said carriage for determining in which denominational row an indexing device shall be set by any of said numeral keys, means to enable the set indexing devices to determine the extent of 20 rotation of the wheels, means operated by the depression of any of said numeral keys to print, to set its own indexing device and restore any previously set indexing device, a zero device for each denominational indexing device movable to restore any previously set indexing device, said zero key common to all of said zero devices, said zero devices being normally out of relation with said key, and means brought into action by 25 the carriage movement for rendering said 30 zero key effective on all of said zero devices.

5. In a combined typewriting and computing machine, the combination with numeral wheels, nine numeral printing keys 35 and a zero printing key, of a letter-feeding carriage under the control of all of said keys, a set of denominational rows of indexing devices settable by said nine numeral keys, means controlled by said carriage for 40 determining in which denominational row an indexing device shall be set by any of said numeral keys, means to enable the set indexing devices to determine the extent of 45 rotation of the wheels, means operated by the depression of any of said numeral keys to print, to set its own indexing device and restore any previously set indexing device, a zero device for each denomination movable to restore any previously set indexing 50 device, a movable bar common to all of said zero devices, said zero devices being normally out of relation with said bar, and means brought into action by the carriage movement for rendering said bar effective on said 55 zero devices.

6. In a combined typewriting and computing machine, the combination with numeral wheels, nine numeral printing keys and a zero printing key, of a letter-feeding 60 carriage under the control of all of said keys, a set of denominational rows of indexing devices settable by said nine numeral keys, means controlled by said carriage for determining in which denominational row 65 an indexing device shall be set by any of

said numeral keys, means to enable the set indexing devices to determine the extent of rotation of the wheels, means operated by the depression of any of said numeral keys to print, to set its own indexing device and 70 restore any previously set indexing device, a zero device for each denomination movable to restore any previously set indexing device, a movable bar common to all of said zero devices, a connection from said zero 75 key to said bar, said devices being normally out of relation with said bar, and means brought into action by the carriage movement to enable said bar, when swung by said zero key, to act on all of said zero devices. 80

7. In a combined typewriting and computing machine, the combination with computing devices, nine numeral printing keys and a zero printing key, of a letter-feeding carriage under the control of all of said keys, 85 a set of denominational rows of indexing devices settable by said nine numeral keys, means enabling any of said numeral keys, on setting its own indexing device, to restore any previously set indexing device, 90 means controlled by said carriage for determining in which denominational row an indexing device shall be set by any of said numeral keys, a general operator for engaging and moving the set indexing devices to 95 determine the extent of movement of the computing devices, a zero device, one for each denominational row of indexing devices, said device movably mounted out of the range of movement of said general operator, and acting to restore any previously set indexing device, and means operated by the movement of said zero key to print, to move said zero device to restore any indexing device in any denominational row as determined by said carriage. 100

8. In a combined typewriting and computing machine, the combination with computing devices, nine numeral printing keys and a zero printing key, of a letter-feeding 110 carriage under the control of all of said keys, a set of denominational rows of indexing devices settable by said nine numeral keys, means controlled by said carriage for determining in which denominational row 115 an indexing device shall be set by any of said numeral keys, a general operator for running into the computing devices the numbers indexed, and mechanism individual to each denominational row of indexing devices for temporarily latching and then releasing any indexing device of the row, said mechanism including means whereby either the general operator, or the zero key when operated to print, may effect the releasing. 120

9. A computing machine having computing devices, means for actuating the computing devices, a series of flexibly mounted digit pins for each denomination, and a general operator for running into the com- 130

puting devices numbers as represented by said pins; and comprising, in combination, a zero pin and a release pin for each denomination, a zero printing key, means brought into operation by said zero printing key for acting on said zero pin to release said digit pins, and means brought into operation from the general operator and acting through said release pin to release said digit pins.

EDWARD THOMAS.
